UNITED STATES PATENT OFFICE.

CHARLES McLAUGHLIN, OF BROOKLYN, NEW YORK, ASSIGNOR TO ROYAL COMB COMPANY, OF LEOMINSTER, MASSACHUSETTS.

DESIGN FOR A BOW-HOLDER.

49,998.

Specification for Design.

Patented Dec. 5, 1916.

Application filed September 1, 1916. Serial No. 118,151. Term of patent 7 years.

To all whom it may concern:

Be it known that I CHARLES McLAUGHLIN, a citizen of the United States, residing at Brooklyn, in the county of Kings and State of New York, have invented a new, original, and ornamental Design for a Bow-Holder, of which the following is a specification, reference being had to the accompanying drawing, forming part of this specification, in which—

Figure 1 is a perspective view of a bow-holder showing my invention; Fig. 2 is a side view; and Fig. 3 an end view thereof.

I claim:—

The ornamental design for a bow-holder as shown.

In testimony whereof I have hereunto affixed my signature.

CHARLES McLAUGHLIN.
